UNITED STATES PATENT OFFICE.

HORACE W. ULRICH, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

1,284,823.

Specification of Letters Patent. Patented Nov. 12, 1918.

Application filed March 30, 1918. Serial No. 225,685.

To all whom it may concern:

Be it known that I, HORACE W. ULRICH, a citizen of the United States, residing at East Orange, in the county of Essex, State 5 of New Jersey, have invented certain new and useful Improvements in Telephone Systems, of which the following is a full, clear, concise, and exact description.

This invention relates to telephone systems and more particularly to such systems in which are employed line or trunk circuits terminating at a central office and provided with line signals.

In such systems at present in use where 15 trunk circuits are employed between central offices and private branch exchanges, if the central office link circuit, at the termination of a conversation, is disconnected from the trunk circuit before the private branch ex- 20 change link circuit is disconnected therefrom, the line signaling device associated with the trunk circuit at the central office operates and furnishes a false signal to the operator. In the case of a line circuit, if 25 the link circuit is disconnected from the line before the receiver is restored to its switchhook, the line signaling device then operates and furnishes a false signal. It is the object 30 of this invention to provide a system in which this false operation of the line signaling device is prevented.

In accordance with this invention a line (or trunk) circuit is provided with a relay which operates upon the connection of a 35 central office link circuit therewith and remains operated upon the disconnection of the link circuit while the line (or trunk) is closed, to prevent the false operation of the line signal, and which is then released 40 upon the subsequent connection of a link circuit with the line (or trunk) to restore the associated line (or trunk) apparatus to normal condition.

For a more complete understanding of 45 this invention reference should be had to the following description considered in connection with the accompanying drawings, wherein Figure 1 shows a line circuit illustrating one embodiment of the invention, and Fig. 2 illustrates another embodiment thereof.

In Fig. 1 of the drawings there is shown a telephone line A terminating at a central

office, at which is located a cord circuit B for extending the telephone line. The telephone line A is provided with the usual line relay 5 and cutoff relay 6, and is also provided with two relays 7 and 8 which co-operate with the line and cutoff relays to prevent the false operation of the line signaling device 9. In Fig. 2 there is shown a telephone line C which is provided with the usual line relay 15 and cutoff relay 16. This line is also provided with a third relay 17 which co-operates with the line and cutoff 65 relays to prevent the false operation of the line signaling device 19.

With this brief description of the drawings in mind, it is thought that the invention may be best understood from a description 70 of the operation of the circuits disclosed.

Subscriber A in initiating a call removes the receiver from the switchhook, thereby causing the operation of line relay 5 over 75 a circuit from battery through the winding of line relay 5, left-hand normal contact of cutoff relay 6 cut over one side of the line, through the switchhook contact, back over the other side of the line, and right-hand normal contact of cutoff relay 6 to ground. Line relay 5, in operating, causes the line lamp 9 to be lighted. The operator upon observing the lighted condition of the line lamp 9 inserts plug 20 of cord circuits 80 B into jack 21, thereby causing the operation of the cutoff relay 6 over a circuit from battery through supervisory lamp 22, resistance 23, sleeve contacts of the plug 20 and the jack 21, normal contact of relay 8, and the winding of cutoff relay 6 to ground. Cutoff relay 6, in operating, disconnects the line relay 5 from the line, which thereupon 85 releases, extinguishing the line lamp 9. The closure of the alternate contact of the cutoff relay 6 causes the operation of relay 7 over a circuit from battery through the right-hand winding thereof and the alternate contact of cutoff relay 6 to ground. While there is a tendency for the supervisory lamp 100 22 to light over the circuit previously traced, supervisory relay 24 operates so soon after the closure of the circuit through the lamp, that a shunt circuit including resistance 25 is established for the lamp before it lights. 105

If, while the receiver is off the switch-

hook, the central office operator withdraws the plug 20 from the jack 21, cutoff relay 6 is immediately released and line relay 5 operates. Relay 7 is of the slow-releasing type so that line relay 5 operates before the alternate contact of relay 7 is opened. Therefore, upon the closure of the contact of line relay 5 a locking circuit for relay 7, which includes the winding of relay 8 is established. This circuit may be traced from battery through the right-hand winding of relay 7, winding of relay 8, alternate contact of relay 7 and the contact of line relay 5 to ground. Relay 8 operates, opening its normal and closing its alternate contact. Since relay 7 is locked up, line lamp 9 cannot be lighted while the receiver remains off the switchhook. If the receiver is restored to the switchhook line relay 5 releases, opening the locking circuit of relay 7 and the energizing circuit of relay 8, which thereupon release their armatures, restoring the apparatus associated with the line to normal condition. If the operator should insert the plug 20 into line jack 21 before the receiver is restored to its switchhook, relays 7 and 8 immediately release. This is brought about by the establishment of a circuit from battery through lamp 22, resistance 23, sleeve contacts of the plug 20 and the jack 21, alternate contact of relay 8, left-hand winding of relay 7, winding of relay 8, alternate contact of relay 7 and contact of line relay 5 to ground. The two windings of the relay 7 are now connected in parallel-opposing, so that the energizing effects of the two windings are neutralized. Relay 7 thereupon releases its armature, opening the energizing circuit of relay 8. Relay 8 releases, reestablishing the energizing circuit of cutoff relay 6. Cutoff relay 6 thereupon operates, disconnecting the line relay 5 from the line.

Subscriber C (see Fig. 2) in initiating a call removes the receiver from the switchhook, thereby causing the operation of line relay 15. Line lamp 19 is thereupon lighted over a circuit from battery through the lamp 19, left-hand normal contact of relay 17 and the contact of line relay 15 to ground. The operator upon observing the lighted condition of the line lamp 19 inserts plug 20 of the cord circuit B into jack 31, thereby causing the operation of cutoff relay 16 over a circuit from battery through the lamp 22, resistance 23, sleeve contacts of the plug 20 and jack 31, right-hand normal contact of relay 17 and the winding of cutoff relay 16 to ground. Relay 16, in operating, disconnects the line relay 15 from the line, which thereupon releases its armature, extinguishing the line lamp 19. Relay 16, in operating, also causes the energization of relay 17 over a circuit from battery through the two windings of relay 17 (which are now

connected in series-aiding) and contact 32 of cutoff relay 16 to ground. Relay 17, in operating, connects cutoff relay 16 in a circuit which includes the right-hand alternate contact of relay 17 and alternate contact 33 of cutoff relay 16. If the operator now withdraws the plug 20 from the jack 31 while the receiver is off the switchhook, cutoff relay 16 immediately releases its armatures, whereupon line relay 15 operates. Relay 17 is of the slow-releasing type, so that line relay 15 closes its contact before relay 17 releases its armatures. Therefore a holding circuit for relay 17 is established from battery through the left-hand winding of relay 17, left-hand alternate contact thereof and the contact of line relay 15 to ground. The circuit hereinbefore traced, which included the two windings of relay 17 connected in series-aiding, was interrupted at contact 32 of cutoff relay 16 upon the release thereof. Relay 17 being maintained energized, prevents the lighting of line lamp 19. If the subscriber restores the receiver to the switchhook the release of line relay 15 causes all apparatus to be restored to normal position. However, if the operator inserts a plug into the jack 31 before the receiver is restored to the switchhook, relay 17 immediately releases its armatures, due to the establishment of a circuit from battery through the supervisory lamp and the sleeve resistance of the cord circuit, sleeve contacts of the plug and the engaged jack 31, right-hand alternate contact of relay 17, contact 34 of cutoff relay 16, right-hand winding of relay 17, left-hand alternate contact thereof and the contact of line relay 15 to ground. The two windings of relay 17 are now connected in parallel-opposing so that the energizing effects of the windings are neutralized. The release of relay 17 immediately reestablishes the original energizing circuit of cutoff relay 16, which operates, disconnecting the line relay 15 from the line.

What is claimed is:

1. In a telephone system, in combination, a telephone line, a line relay therefor, a line signal, a slow release relay coöperating with the line relay to control the line signal, a cutoff relay controlling the line relay, a link circuit for extending the telephone line, an energizing circuit for the slow release relay established upon the connection of the link circuit with the telephone line, a locking circuit for the slow release relay completed upon the disconnection of the link circuit from the telephone line to prevent the operation of the line signal while the line is closed, and a deenergizing circuit for the slow release relay established upon the subsequent connection of the link circuit with the telephone line.
2. In a telephone system, in combination,

- a telephone line, a line relay therefor, a line signal controlled by the line relay, a link circuit for extending the telephone line, a cutoff relay operating upon the connection 5 of the link circuit with the telephone line to remove the line relay from the control of the telephone line, and a slow release relay controlling the restoration of the line relay to the control of the telephone line when the 10 link circuit is disconnected therefrom and the removal of such control therefrom upon the subsequent connection of the link circuit with the telephone line.
3. In a telephone system, in combination, 15 a telephone line, a line relay therefor, a line signal, a slow release relay coöperating with the line relay to control the line signal, a cutoff relay controlling the line relay, a link circuit for extending the telephone line, 20 an operating circuit for the cutoff relay established upon the connection of the link circuit with the telephone line, an energizing circuit for the slow release relay established upon the operation of the cutoff relay, a circuit 25 established upon the disconnection of the link circuit from the telephone line for maintaining the slow release relay energized and the operating circuit of the cutoff relay open, and a circuit including a winding 30 of the slow release relay established upon the subsequent connection of the link circuit with the telephone line for causing the closure of the operating circuit of the cutoff relay.
- 35 4. In a telephone system, in combination, a telephone line, a line relay therefor, a line signal, a slow release relay having two windings and coöperating with the line relay to control the line signal, a cutoff relay 40 controlling the line relay, a link circuit for extending the telephone line, an operating circuit for the cutoff relay established upon the connection of the link circuit 45 with the telephone line, an energizing circuit for the slow release relay established by the operation of the cutoff relay and including one of its windings, a circuit established upon the disconnection of the link circuit from the telephone line and including the one winding thereby to maintain the 50 slow release relay energized and the operating circuit of cutoff relay open, and a second circuit including the second winding of the slow release relay established upon the subsequent connection of a link circuit with 55 a telephone line for rendering the slow release relay differential thereby to release the slow release relay and close the operating circuit of the cutoff relay.
5. In a telephone system, in combination, 60 a telephone line, a line relay therefor, a line signal, a slow release relay coöperating with the line relay to control the line signal, a cutoff relay controlling the line relay, a link circuit for extending the telephone line, an 65 operating circuit for the cutoff relay established upon the connection of the link circuit with the telephone line, an energizing circuit for the slow release relay established upon the operation of the cutoff relay, a 70 locking circuit for the slow release relay established upon the disconnection of the link circuit from the telephone line to prevent the operation of the line signal while the line is closed, a fourth relay energized upon 75 the establishment of the locking circuit to open the operating circuit of the cutoff relay, a deenergizing circuit for the slow release relay established upon the subsequent connection of the link circuit with the telephone line for causing the release of the fourth relay and the closure of the operating circuit of the cutoff relay.

In witness whereof I hereunto subscribe my name this 25th day of March, A. D. 1918. 80
HORACE W. ULRICH. 85
